UNITED STATES PATENT OFFICE

JOHN N. HELTZEL, OF WARREN, OHIO

ROAD BUILDING APPARATUS

Application filed August 14, 1929. Serial No. 335,800.

The present invention relates to concrete road building apparatus, and one object of the invention is the provision of novel means for installing a joint in a concrete road or 5 pavement.

Another object is the provision of means for installing a lower or bottom joint in the road or pavement.

A further object is the provision of means 10 for conveniently placing longitudinal reinforcing rods in the concrete.

Another object is the provision of means for producing tunnels in the road or pavement, in order to reduce the volume of concrete required, and to provide drainage channels 15 for water under the slabs.

A further object is the provision of novel means for sub-grading the sub-base or road-bed.

20 With the foregoing and other objects in view, which will be apparent as the description proceeds, the invention resides in the construction and arrangement of parts, as hereinafter described and claimed, it being 25 understood that changes can be made within the scope of what is claimed without departing from the spirit of the invention.

The invention is illustrated in the accompanying drawings, wherein—

30 Figure 1 is a plan view of the apparatus.

Fig. 2 is a front view thereof.

Fig. 3 is a cross section on the line 3—3 of Fig. 1.

35 Fig. 4 is a longitudinal section on the line 4—4 of Fig. 1.

Fig. 5 is a cross section of a completed joint.

40 Fig. 6 is a cross section of a brick-surfaced road built by the apparatus.

Figs. 7, 8 and 9 are cross-sections of a type 45 of joint heretofore used and illustrating how the joint opens up to permit water to pass through.

Fig. 10 is a perspective view of a modified construction including a joint strip supporting runner movable on dowel rods.

Fig. 11 is a fragmentary perspective view of a different runner.

50 Fig. 12 is a fragmentary perspective view

of still another variation in the construction of the runner.

Fig. 13 is a perspective view depicting another variation wherein the joint strip blade or runner is movable on pedestals.

Fig. 14 is a perspective view of still another variation of joint strip supporting and placing means.

Fig. 15 is a perspective view illustrating another modification in the joint strip placing or depositing means.

Fig. 16 is a perspective view of a modified form of device for positioning the joint strip in the plastic concrete.

Fig. 17 is a cross section to a joint illustrating a joint strip between the sub-base and surface of the road.

Fig. 18 is a cross section of a joint showing the joint strip flush with the surface of the road.

Fig. 19 is a cross section of a joint showing a joint strip extending from the sub-base to the surface of the road.

Fig. 20 is a cross section of a joint illustrating a division plate having an offset intermediate its upper and lower edges.

Fig. 21 is a perspective view illustrating a further modification in the joint strip depositing means.

Fig. 22 is a perspective view showing a further variation of joint producing means.

A transverse angle iron or member 1 is provided to move over the sub-base, and carries transversely spaced teeth or rooters 2 to score the sub-grade to the elevation or depth desired. The teeth 2 are adjustable vertically, being provided with vertical slots 3 receiving clamping bolts 4 engaging the member 1.

Arches 5 are provided at the ends of the member 1 and have wheels 6 mounted therein to move on the side forms or rails 7 between which the road is built. Said arches 5 have portions 8 overlapping the terminals of the member 1 and provided with slots 9 receiving clamping bolts 10 secured in the member 1, thereby supporting said member from the wheels, and providing for the extension and contraction of the sub-grader constituting the member 1, teeth 2 and wheel mounted members or arches 5.

Chains 11 or other draft members are connected to the member 1 for pulling same forwardly, and may be connected to a concrete mixer, tractor, or other draft means 12.

5 A runner or mandrel 13 is trailed from the member 1, the forward terminal of said runner being secured to said member. The runner, as shown, constitutes a T-iron with its flanges 14 adapted to rest on the sub-base and the web 15 extending upwardly.

10 The runner or mandrel 13 provides means for positioning a strip 16 of paper, fabric, sheet metal or other suitable material in the lower portion of the concrete road, and as shown the strip is used to provide a longitudinal central joint. The strip 16 passes rearwardly from a roll 17 suitably mounted on the forward portion of the runner 13, and a grooved or double wheel 18 is disposed 15 20 astride the web 15 of the runner to fold the strip 16 or double same transversely over and astride the web 15.

25 The wheel has its axle connected by links or bars 19 with the axle of the roll 17, to permit the wheel 18 to be raised, said wheel being sufficiently heavy to fold the strip 16 over the web 15.

30 The strip 16 is thus doubled on a longitudinal line with its bend or fold uppermost and its edges lowermost, and the runner or mandrel 13 is pulled forwardly while the strip remains embedded in the concrete, this arrangement being similar to that shown in Fig. 9 of application Serial No. 235,977 35 filed Nov. 26, 1927.

Transversely arched cores 20 are trailed from the member 1 by means of chains 22 or other flexible elements, for producing tunnels in the road, said cores being suitably 40 spaced at opposite sides of the runner 13.

45 In building the road, the plastic concrete is poured over the cores 20 and the folded strip 16 on the runner 13. If desired, tunnel liners 22 of stiff paper, fabric, sheet metal, or other suitable material, may be placed on the cores 20 to remain in the tunnels. The plastic concrete is poured on the sub-base to a depth to produce the lower course or layer of the road, and the reinforcing mesh, fabric or rods 23 are then placed 50 on this lower course, after which additional concrete is added to produce the upper course or layer which is finished off in the usual manner.

55 The apparatus is then drawn forwardly for a distance slightly less than the length of the cores 20, so that the rear ends of the cores remain in the tunnels, and as the runner 13 is moved forwardly the strip 16 is 60 pulled from the roll 17 and is folded over the runner. The pouring of the concrete, placing of the reinforcing mesh or rods and completion of the next section of road is then carried on as above described, so that 65 the road is built step by step.

If a concrete mixer is used at the point where the road is built, it may be employed for pulling the apparatus forwardly with it, and the concrete may be dumped from the mixer over the cores 20 and folded strip 16. 70 If the plastic concrete is brought from a distance or central plant, then ramps may be placed over the member 1 to permit the trucks or other carriers to move over the member 1 for dumping the plastic concrete over the cores 20 and folded strip 16. A tractor or other draft means would be used for pulling the apparatus forwardly as the building of the road progresses, when a tractor concrete mixer is not employed. 75 80

The liners 22, when used, will remain in the tunnels and will support the plastic concrete until it has set, although if the concrete sets sufficiently fast the liners 22 may be omitted. The tunnels thus produced will lessen the volume of concrete required, to provide for economy. 85

Moreover, the tunnels will provide drainage channels for water in order that same may pass off quickly from the sub-base. 90

The folded strip 16 will separate the concrete at the bottom or along the sub-base, and the reinforcement extends over said strip so as to tie the slabs of concrete together. 95

An upper joint 24 is formed in the road above the strip 16. The upper longitudinal as well as transverse joints may be produced while the concrete is plastic or may be sawed or otherwise produced in the concrete after it has set. As shown in Fig. 5, a groove is 100 formed in the concrete above the reinforcement 23 and in the line of the strip 16, and is filled with tar, asphaltum or other sealing material. The concrete will break between the strip 16 and joint 24, as seen in Fig. 5, 105 and the slabs may flex, due to heaving or depression thereof, without appreciably straining the reinforcement 23, in that the lower joint permits the slabs to be depressed, while the upper joint permits the slabs to be raised, 110 such as by the heaving of the sub-base, without imposing injurious tensile strain on the reinforcement 23. This is of advantage over the type of joint shown in Figs 7, 8 and 9, 115 embodying the division plate 30 disposed between the slabs and through which the tie rods or reinforcement 23a extends.

When the slabs are depressed, as seen in Fig. 8, they contact to form fulcrums, as at 120 31, at the lower edge of the plate 30, thereby stretching the reinforcement 23a, and when the slabs return to normal position, as seen in Fig. 9, the joint will be opened, the elongation of the reinforcement 23a separating the slabs sufficiently so that water can seep or 125 flow downwardly between the slabs. This is objectionable in that the sub-base may be washed away and the road weakened so that it may break down under traffic conditions.

Such conditions are avoided with the pres- 130

ent invention in producing upper and lower compressible joint members in the concrete to permit of the upward and downward movements of the slabs relatively to one another 5 without stretching or unduly straining the reinforcement, and the joint will remain closed or sealed.

The apparatus, modified if necessary, may also be used for producing transverse joints 10 or tunnels in the road. The tunnel liners 23 may also be corrugated transversely to enable thinner material to be used.

Tubes 25 are trailed from the arches 5 and some of the teeth 2, with their rear terminals 15 in the plastic concrete, to enable reinforcing rods 26 to be inserted rearwardly through said tubes to be embedded in the concrete. As shown, the rods are embedded in the concrete adjacent to the opposite sides of the 20 road and at opposite sides of the longitudinal joint.

Fig. 6 illustrates a road with a concrete base constructed in accordance with the present invention, and having a brick surface. 25 There is also shown the use of dowel rods 23a in place of reinforcing mesh. Longitudinal reinforcing rods 26a are also shown embedded in the concrete.

Fig. 10 illustrates a runner or strip 14b 30 with angle irons 15b secured thereon to provide a slot to receive the lower edge portion of the joint strip 16b, and said runner has a projecting portion 1b at the forward end for the connection of the draft chain or element 35 11b for pulling said runner forwardly as the building of the road progresses. The runner 14b is supported by transverse dowel rods 32 which are in turn supported by stakes 33 driven into the sub-base and having apertures receiving said rods. The joint strip is thus embedded in the concrete at the upper surface thereof spaced above the sub-base.

A stake 34 may be driven through an aperture in the portion 1b into the sub-base for 45 preventing accidental longitudinal movement of the runner 14b.

A gage 35 may be employed for spacing the joint strip and runner the proper distance from the side form rail 36.

Cap strips 37 are fitted astride or over the upper edge of the joint strip, and have draft means 38 at the forward end for pulling said cap strips forwardly with or independent of the runner 14b, or said cap strips may be 55 left in place on the joint strip to be removed subsequently. Figures 21 and 22 represent further modification of aligning strips.

The runner 14b is moved forwardly as the building of the road progresses, thereby 60 leaving the joint strip deposited in the concrete.

As shown, dowel rods 39 extend through the joint strip for supporting same in the concrete and to assist in tying the slabs together. 65

The joint strip 16b may be of any suitable flexible or stiff material, and the cap strips 37 are placed over the joint strip to protect same during the pouring and finishing of the concrete over the sub-base and joint strip. 70 The cap strips may be moved forwardly as the building of the road progresses, or may be left in place to be pulled out later.

Fig. 11 shows a runner 14c to slide on the sub-base, and having angle irons or upstanding flanges 15c to receive the joint strip 16c which has dowel rods 39c extending through same, and a cap strip 37c is placed on the joint strip. This arrangement is used when the joint strip is of a height substantially 80 equal to the thickness of the slab.

Fig. 12 illustrates a spacer 14d between angle irons 15d to provide a runner to move on the sub-base, with dowel rods 39d extending through the joint strip 16d.

Fig. 13 illustrates a plate 15e disposed on edge and having an outstanding flange or runner 14e at one side, and said plate is formed at its forward end with a housing 40 containing the roll 17e from which the joint strip 16e passes along one side of the plate 15e above the flange 14e to be deposited in the plastic concrete. The housing or case 40 may be disposed at any suitable angle or in any desired position, and completely encloses the roll 17e so that the plastic concrete may be dumped over said housing. The housing preferably has a window 41 at the top thereof to enable the roll 17e to be observed, so that a new roll may be inserted when the supply in the housing is exhausted. The housing 40 and plate 15e are pulled forwardly as the building of the road progresses.

The plate 15e is supported by pedestals 42 secured by stakes 33e on the sub-base, and said pedestals have apertured ears for supporting the transverse reinforcing rods or dowels 39e, and longitudinal reinforcing rods 26e may also be inserted in apertures in said pedestals. The pedestals have slots 44 in which the lower edge portion of the plate 15e moves, for guiding said plate along the line of the joint.

Fig. 14 illustrates a vertical plate 15f along one side of which the joint strip 16f is disposed, to be embedded in the plastic concrete, and the plate 15f has a base or runner flange 14f to slide on the dowel rods 32f supported by the stakes 33f. Said plate 15f has its upper edge portion bent back to provide a cap 37f to be disposed over the upper edge of the joint strip. The plate 15f supports and protects the joint strip during the pouring and finishing of the concrete, and is moved forwardly at intervals, leaving the joint strip deposited in the concrete.

Fig. 15 illustrates the use of a bottom strip 14g on which the joint strip 16g is disposed, with a cap strip 37g on the upper edge of the joint strip, said strips 14g and

37g have flanges 15g overlapping the joint strip. Dowel rods 39g extend through the joint strip, and stakes 33g are driven into the sub-base to guide the strips 14g and 37g which are pulled forwardly as the building of the road progresses. The strips 14g and 37g may either be drawn forwardly simultaneously or separately.

Fig. 16 illustrates a blade 15h to move in the plastic concrete at the point of pouring and finishing, and the strip 16h passes from the roll 17h across a guide roller 45 at the forward end of the blade 15h. The strip passes rearwardly across one side of said blade to be deposited in the concrete. The blade has upstanding shanks 46 for mounting the blade from a carriage, and a mechanically or manually operated finisher 50 moves across the upper edges of the blade 15h and strip 16h to finish the surface of the concrete at opposite sides of the joint.

A pair of disks 18h are provided to trail the blade 15h and support the strip in vertical position. Said strips 18h are trailed by links 19h connected to the rear end portion of the blade 15h, and an adjusting link or brace 47 is provided for adjusting the strips 18h upwardly and downwardly. Said brace 47 has a slot 48 receiving a clamping bolt 49 carried by the blade 15h, so that when the bolt 49 is loosened the disks 18h may be raised and lowered with the links 19h. A member 51 secured on the blade 15h extends over the upper edge of the joint strip or material 16h and protects it against the action of the reciprocating float or finisher 50, and said member has a depending flange which holds the strip 16h against the side of the blade.

Figure 17 illustrates the joint strip 16i between the top and bottom of the slab, with the dowel rod 39i extending through said strip. This is the type of joint produced by the device shown in Figure 12.

Figure 18 illustrates the joint strip 16j at the surface with the dowel rod 39j below said strip, which is the type of joint produced by the device shown in Fig. 10. This joint strip 16j may consist of various kinds of material. If premolded or similar types of material is used, it may remain deposited in the concrete. However, removable steel joint plates may be used, which may be later withdrawn from the plastic concrete, leaving an open groove, which may be filled later with any suitable kind of bituminous or asphaltic material to produce a poured joint.

Figure 19 shows the joint strip 16k of a height equal to the thickness of the slab, with the dowel rod 39k extending through said strip. This type of joint is produced by the devices shown in Figures 11 and 15.

Fig. 20 illustrates the joint strip 16m with an offset portion through which the dowel

rods 39m extend, to provide a tongue and groove joint between the slabs.

The joint strip 16f shown in Fig. 14 may be of composition, fabric, or other flexible material, and has reinforcing wires or cables 70 embedded therein.

The strips 14g and 37g shown in Fig. 15 may be flexible with the joint strip 16g so that the joint may be extended along curved lines.

Fig. 21 illustrates a plate 37n movable on the surface of the plastic concrete and having a pair of depending blades or flanges 15n between which the joint strip 16n of any suitable material may pass, to be deposited in the concrete as the plate 37n is drawn forwardly. Said plate in moving on the plastic concrete will limit the depression of the device, and the device may be moved forwardly by any suitable means. The joint strip may be of paper, ribbon steel, or other suitable material. The joint member may also be used without the joint strip, for producing an open groove.

Fig. 22 illustrates a T-iron or member movable in the plastic concrete, so that the flanges 37p produce a channel 52 while the depending web 15p produces a groove 53. The groove will control the breaking of the concrete, while the channel may be filled with concrete of a different color or other suitable material for producing a traffic line.

Having thus described the invention, what is claimed as new is:

1. A road building apparatus comprising a runner, and means for supplying a folded strip over said runner.

2. A road building apparatus comprising a runner, and means for folding a strip over said runner to be embedded in the concrete.

3. A road building apparatus comprising a runner, means for supplying a strip over said runner, and means for folding said strip downwardly on the runner.

4. A road building apparatus comprising means for supplying a joint strip, and means for folding said strip and positioning it with its fold uppermost and its edges lowermost.

5. A road building apparatus comprising a runner having bottom flanges and an upstanding web, and means for folding a strip over said web.

6. A road building apparatus comprising a runner having bottom flanges and an upstanding web, and means for supplying a strip over said web to be folded thereon.

7. A road building apparatus comprising a runner having bottom flanges and an upstanding web, means for supplying a strip over said web, and means for folding said strip down on the web.

8. A road building apparatus comprising tunnel cores movable on the sub-base of a road, and means for pulling said cores forwardly as the building of the road progresses.

9. A road building apparatus comprising

tunnel cores movable on the sub-base of a road under construction, means for pulling said cores forwardly as the building of the road progresses, and tunnel liners adapted to be positioned on said cores.

5 10. A road building apparatus comprising a member over which a joint strip is foldable, and a pair of disks mounted astride said member.

10 11. A road building apparatus comprising a runner having an upstanding portion over which a joint strip is foldable, and a pair of disks mounted for rotation and overlapping said portion.

15 12. A road building apparatus comprising means for supplying a joint strip, a pair of disks mounted to work astride said strip, and means to support the strip beneath the disks.

20 13. A road building apparatus comprising means for supplying a joint strip, a runner for receiving the joint strip from said means and sliding longitudinally under the joint strip, and means to force the joint strip downwardly upon said runner.

25 14. A road building apparatus comprising means for supplying a joint strip, a runner having an upstanding joint strip supporting portion for receiving the joint strip thereon, and means for pressing the joint strip downwardly upon said upstanding portion.

30 15. A road building apparatus comprising a pair of disks disposed to work in plastic concrete, and means for supplying a joint strip beneath said disks.

35 In testimony whereof I hereunto affix my signature.

JOHN N. HELTZEL.
